CLAIM

The ornamental design for a dog harness, as shown and described.

DESCRIPTION

FIG. 1 is a top, front, left perspective view showing our design for a dog harness.

FIG. 2 is a left side elevation view thereof.

FIG. 3 is a front elevation view thereof.

FIG. 4 is a right side elevation view thereof.

FIG. 5 is a rear elevation view thereof.

FIG. 6 is a top plan view thereof.

FIG. 7 is a bottom plan view thereof; and,

FIG. 8 is a top, front, left perspective view of the dog harness of FIG. 1, shown in condition of use.

The dashed lines in FIGS. 1 through 8 show portions of the article that form no part of the claimed design. The dash-dot-dash line showing of a dog in FIG. 8 depicts environmental subject matter and forms no part of the claimed design.
